GRAIN-DOOR.

No. 891,926.

Specification of Letters Patent. Patented June 30, 1908.

Application filed November 19, 1907. Serial No. 402,805.

To all whom it may concern:

Be it known that I, EDGAR B. GILLELAND, a citizen of the United States, residing in Topeka, in the county of Shawnee and State 5 of Kansas, have invented a new and useful Improvement in Grain-Doors, of which the following is a specification.

My invention relates to grain-doors for freight cars, of the vertically-sliding type 10 adapted to be swung up against the roof of the car and hung by a carline hook when not in use.

The object of my invention is to improve generally upon grain-doors, to provide guides 15 which are pivoted at the top of the car-door and which are adapted to be swung up against the roof of the car with the grain-door when the grain-door is not in use so as to not have any guides or brackets projecting from the door-jamb, to provide a simple, strong, and durable arrangement of the grain-door with a swinging guide of this kind, which may be operated with ease and without binding, and to provide the various 20 parts and combinations hereinafter set forth more in detail.

My invention consists of an arrangement 25 of a pivoted guide and a door slidably mounted thereon, so that the door and guide may be swung up against the roof of the car and suspended on the carline hook.

It further consists of a U-shaped rod having the upper ends of its legs pivoted to the door-cap and a grain-door mounted thereon 30 so as to be slidable thereon vertically; it further consists of a U-shaped rod having the upper ends of its legs pivoted to the door-cap and a grain-door mounted thereon so as to be slidable vertically thereon with bearing 35 for the legs of the rod at the top of the grain-door and a slidable bearing secured to the horizontal portion of the rod with a vertical track on the grain-door engaged by said 40 slidable bearing; and it further consists of the combinations hereinafter pointed out and claimed.

In the drawings accompanying and forming 45 part of this specification, and in the description of the drawings, I have shown my invention in its preferred form and have shown the best mode of applying the principles thereof; but it is to be understood that the invention itself is not confined to the

exact details of those drawings and of that description; and that I contemplate changes 55 in form, proportions, materials, and arrangement, the transposition of parts, and the substitution of equivalent members, within the scope of the appended claims, without departing from the spirit of the invention. 60

Figure 1 is an elevation view, taken from outside the car, of a grain-door made in accordance with my invention, sections of the legs of the U-shaped rod and of the door-jambs being removed for convenience in illustration, and portions of the door-jambs being broken away in order more fully to disclose the grain-door and the mode of fastening it. Fig. 2 is an end view of the improved grain-door attached to the car, the near door-jamb being removed, and the grain-door proper being raised on its guide ready to be swung up against the roof of the car; the position of the grain-door when hung on the carline hook being shown in dotted outline. 70 Fig. 3 is a vertical sectional view of the grain-door in part, through the line 3 of Fig. 1, showing the arrangement of one of the twin relief-doors. Fig. 4 is a view of the lower portion of the door and one of the two hooks 80 for holding the door up on the U-shaped rod. Fig. 5 is a sectional view of one of the relief-doors, through the line 5 of Fig. 1. Fig. 6 is an enlarged view of the upper edge of the grain-door showing the arrangement of one 85 of the bearing-brackets for the legs of the U-shaped rod; and Fig. 7 is a sectional view through the line 7 of Fig. 6. Fig. 8 is also a view of the upper edge of the grain-door showing the arrangement of the central vertically disposed track on the face of the grain-door and the central bearing for the rod; and Fig. 9 is a sectional view through the line 9 of Fig. 8. Fig. 10 is an elevation view, taken from outside the car, showing the upper portion 90 of the grain-door and all of the overlap door, the bearing brackets and other fixtures being removed. Fig. 11 and Fig. 12 show other methods of securing the hinge to the door cap. 95

Similar reference characters indicate like or corresponding parts throughout the several views.

12, 12 represent the door-jambs of a car-door, and 13 is the cap. 100
14 represents a carline, and 15 is the car-

line hook which may be of the kind ordinarily used for supporting the inner end of the up-turned grain-door.

16 is the grain door proper, which may be 5 of any suitable construction. I prefer to use a grain-door with the battens and braces arranged as illustrated in Fig. 1, with the end battens 17, 17, top and bottom edge-strips 18, 18, the middle battens 19, and the diagonal braces 20, 20, with the other reinforcements and braces hereinafter to be mentioned. Arranged at the top of the grain-door, one at each side, are the guide-rod brackets 21, 21, each having a hole there- 10 through 22 for engaging the respective guide-rods 35, 35.

23 is a guide-way secured to the outside of the grain-door by rivets 26, 26, extending from top to bottom of the grain-door and 20 centrally disposed thereon, the upper end preferably projecting slightly above the upper edge to form a brace for the overlap door. This guide-way is substantially T-shaped; though by making it with the channel 25 24 and the flared edges 25, 25, the rivets may be set in the channel, and the guide-way, or track, may be rolled, thus giving a more satisfactory track than the ordinary tee irons.

30 27 is a guide-way bracket adapted by its inturned edges 28, 28 to embrace said guide-way or track, so as to be slidable up and down thereon; and the bracket is rather elongated so that it will not bind or turn side- 35 wise. There is an opening 29 through the guide-way bracket at right-angle to the guide-way for engaging the rod 33 hereinafter to be referred to in detail. The bracket has an extension 30 with a hole 31 to be engaged by 40 the carline hook as will be hereinafter detailed.

33 is a single integral rod of a U-shape, as 45 illustrated in Fig. 1. The legs of the rod form the guide-rods 35, 35 for the grain- door, and the base 34 forms a continuous and rigid connection between the two guide-rods across the front of the door and passes 50 through the guide-way bracket 27, the guide-rods passing through the guide-rod brackets 21, 21. The upper ends of the guide-rods engage suitable hinges 37, 37, respectively, by 55 their overturned ends 36, said hinges being secured to the car-door cap, in any suitable manner, as illustrated in various forms in Figs. 2, 11, and 12. The connecting rod fits snugly in the opening 29 through the guide-way bracket 27, and the rod may be pinched 60 38, 38 on each side so as to prevent its movement through said opening. The guide-rods fit rather loosely in the openings 22. This arrangement of the brackets prevents the grain-door from binding, and from tending to turn sidewise on the guides, but admits of some slight range of action forward and

backward, to fit the door snugly against the 65 inside plates on the door-jamb, and to make allowance for various methods of hinging the guide-rods, etc.

When the door is down in place on the floor and against the door-jambs (as in Fig. 1), the guide-way bracket 27 is at the top of the door, and so too is the connecting rod 34. However, the same apparatus may be applied to a shorter door-way, the only difference being that the connecting rod and 75 guide-way bracket would not have, when the door is down, quite so high a relative position. This adaptability of my grain-door to various heights of door-ways is an important feature of my invention. Guide-lugs 80 39, 39 may be placed on the face of the grain-door to engage the door-jambs, and thus prevent any lateral motion. And drop-latches 40, 40 may be provided to be dropped into an opening 42', 42' back of the plate 41 85 on the inside of the door-jamb to hold the grain-door closely against the door-jamb while the car is being loaded.

An overlap door 42 may be hinged to the grain-door proper by means of hinges 43, 43, 90 with elongated eyes 44, which permit the overlap door to settle down on the upper edge of the lower door and thus to take up the wear on the upper edge and compensating for splintering, etc. Preferably the overlap 95 is provided with end battens 44', 44', a middle batten 45, and the diagonal braces 46, 46. The middle batten fits against the projecting upper end of the guide-way 23, whereby the overlap is prevented from bowing 100 outwardly in the middle.

I prefer to equip my grain-door with twin relief-doors arranged on opposite sides of the middle batten 19, as shown in Fig. 1. Each relief door 47 is fitted over an opening 48 105 through the body of the grain-door. Along the outer edge of each relief door is a brace 49. Metal strips 50, 50, 55, 55, are nailed to the batten and braces to form guides for the relief doors, the outer strips 55, 55 being extended upward over the diagonal braces 20, 20. Across the bottom of the relief doors is another metal strip 51, which acts as a further reinforcement. The relief doors are thus adapted to slide up and down in the 110 guide-ways, their upward action being limited by the lugs 52, 52 turned down from the strips. I prefer to slant the braces 49, 49 slightly outwardly, and to shape the relief doors accordingly, so as to make a tight fit 115 when the relief door is down, but permitting it to be raised without friction so far as its edges are concerned. The relief door being made usually of a single board, I reinforce it with a metal strip 53 which crosses its front, 120 its edges, and partly around the back, being countersunk around the portions where the guide-ways are engaged, 54. 56 is an up-

turned lug by which the relief-door may be raised.

57, 57 are a pair of hooks adapted to engage the connecting rod 34 of the guide-rods 5 when the grain-door is raised preparatory to swinging it up against the roof of the car. When the grain-door is raised the connecting rod having some springiness readily engages these hooks and prevents the door 10 from falling, the door being held in the position shown in Fig. 2. When the door is to be lowered, the person operating it being inside the car, need only to grasp the lower edge of the door with his hand his fingers engaging the rod 34 near the hooks and drawing rod and door toward each other by the compression of the hands and fingers, thus permitting the rod to be free from the inner points of the hooks, and permitting the door 20 to be lowered.

Obviously, where the grain is unloaded by the suction process, the relief-doors need not be used, though their presence in the grain-door is not objectionable, and the arrangement 25 of the braces and metal strips is a distinct advantage in the matter of reinforcing the door. Where the relief-door process of unloading is used, the main pressure behind the door may be relieved by opening the 30 twin relief-doors. When the pressure is sufficiently relieved, the grain-door may be raised, as by hand-holds not here shown, the guides and brackets insuring a direct vertical movement of the door without binding. 35 The operator may first raise the door until he can grasp the lower edge, then step back toward the middle of the car, and then "skid" the door up, the guides forming tracks for the brackets as bearings, thus relieving the 40 operator of considerable "dead" weight. The whole apparatus, door and guides, may then be swung, on hinges 37, 37, up against the roof and secured by the carline hook 15 which engages the hole 31 in extension 30 of 45 the guide-way bracket 27.

It will be readily understood that no alteration of the car door cap is necessary for the application of my grain-door, and that when the grain-door is swung up against the roof, 50 the guides too are up, and no tracks, guides, or brackets of any kind are attached to the door-jams to weaken same or to be in the way or take up space. It will also be noted that with my arrangement of the U-shaped 55 rod to form the guide-rods and also the rigid connecting rod across the face of the door with the guide-way on the door and the guide-way bracket, the door may be raised and lowered thereon without binding or

turning sideways, and with a minimum of 60 effort on the part of the operator.

What I claim is:

1. The combination of a grain-door, a pair of guides hinged at the top of a car doorway, bearings secured to the upper part of 65 the grain-door slidably engaging said respective guides, a rod rigidly connecting said guides below said bearings, a vertical guide secured to the grain-door, and a bearing secured to said connecting rod and slidably 70 engaging said last-named guide.

2. The combination of a grain-door, a pair of guide-rods hinged to the cap of a car doorway, bearing brackets secured to the upper part of the grain-door slidably engaging said 75 respective guide-rods, a rod rigidly connecting said guide-rods below said bearings, a vertical guide-way secured to the grain-door, and a bearing bracket secured to said connecting rod and slidably 80 engaging said guide-way.

3. The combination of a grain-door, a pair of guides hinged at the top of a car doorway, bearings secured to the upper part of 85 the grain-door slidably engaging said respective guides, a rod rigidly secured to the said guides below said bearings, a vertical guide secured to the grain-door, a bearing secured to said connecting rod and slidably 90 engaging said last-named guide, means for sustaining 95 the grain-door on said first-named guides when the said grain-door is raised thereon, and an extension on said last-named bearing adapted to be engaged by the carline hook of a car.

4. The combination of a grain-door, a U-shaped integral rod the upper ends of its legs pivoted to the cap of a car-door, bearing brackets slidably engaging said respective legs as guides and secured to the upper part 100 of the grain-door, a vertical centrally disposed guide-way secured to the face of the grain-door, an elongated bearing bracket secured to the connecting portion of said U-shaped rod and slidably engaging said guide-way and provided with an extension adapted 105 to be engaged by the carline hook, and hooks secured to the lower portion of the grain-door to engage the connecting portion of the U-shaped rod when the grain door is raised. 110

In testimony whereof I have hereunto signed my name in presence of subscribing witnesses.

EDGAR B. GILLELAND.
